UNITED STATES PATENT OFFICE.

GEORGE WESLEY MURRAY, OF ATLANTIC CITY, NEW JERSEY.

GAS-BROILER.

1,103,992.

Specification of Letters Patent. Patented July 21, 1914.

Application filed May 21, 1913. Serial No. 768,995.

To all whom it may concern:

Be it known that I, GEORGE W. MURRAY, a citizen of the United States, and a resident of Atlantic City, in the county of Atlantic and State of New Jersey, have invented a new and Improved Gas-Broiler, of which the following is a full, clear, and exact description.

The object of the invention is to provide a new and improved gas stove, more especially designed for broiling meats and other food products, and arranged to subject the meat to be broiled to the full upward force of the heat to insure proper broiling, to protect the gas jets from becoming clogged up by drippings from the meat during the broiling operation, and to shield the cook from the flare of the gas flames.

In order to accomplish the desired result, use is made of a series of perforate gas pipes arranged on top of the gas stove, and a frame supported on the gas stove and provided with inverted V-shaped hoods extending above the gas jets of the said pipes.

A practical embodiment of the invention is represented in the accompanying drawings forming a part of this specification, in which similar characters of reference indicate corresponding parts in all the views.

Figure 1 is a front elevation of the improved gas stove; Fig. 2 is a transverse section of the same on the line 2—2 of Fig. 1; Fig. 3 is a perspective view of the griddle frame, part of the front being broken out; Fig. 4 is a cross section of the stove on the line 4—4 of Fig. 1 and showing more particularly the sliding connection between the griddle frame and one side bar of the gas stove; Fig. 5 is an enlarged sectional front elevation of one side of the griddle frame and its bearing on one of the side bars of the stove; and Fig. 6 is a perspective view of a modified form of the griddle frame for use when cooking, or heating sad irons and the like.

A series of transversely-extending gas pipes A are arranged parallel on top of the stove frame B, and the said gas pipes A are spaced suitable distances apart and each is provided on top with a row of perforations A' (see Figs. 2 and 5) to provide gas jets or burners. The front ends of the gas pipes A are connected with a distributing pipe C arranged in front of the frame B and connected with a service pipe D by the use of pipes E each having a valve E' for control-

ling the flow of the gas from the service pipe D into the distributing pipe C. The ends of the distributing pipe C are provided with air inlet valves C' of the usual construction so that when the valves E' are opened a mixture of gas and air passes into the distributing pipe C and from the latter to the gas pipes A to provide an inflammable mixture to be burned at the openings A'. 60

Over each perforate gas pipe extends a hood F approximately of inverted V shape, the lower edges of the members of each hood being arranged on opposite sides of the corresponding gas pipe A but adjacent hoods F are spaced from each other, as will be readily understood by reference to Figs. 1 and 5. It will be noted that the sides or edges of the hoods project downward below the top perforated portion of the gas pipes so that they protect the flame from side draft and thoroughly utilize the heat of the same. The front and rear ends of the hoods F are secured to the front and rear bars G', G² of a frame G having depending side bars G³ provided at their lower edges with friction rollers G⁴, adapted to travel in the bottoms of grooves B' formed in the side bars B² of the gas stove frame B. By the arrangement described the griddle frame G with its hoods F can be readily slipped in place on top of the gas stove so that the hoods F extend over the gas pipes A as previously explained, and when the gas is lighted the heat produced by the flames is caused to pass up between adjacent hoods F onto the meat or other food product to be broiled and resting on top of the griddle G. It will also be noticed that by the arrangement described the heat is adapted to pass onto the entire surface of the meat so as to conveniently broil the same, and the openings A' are protected against fat or other drippings from the meat under treatment so that the said openings A' are not liable to be clogged up. As the flames extend under the hoods F, it is evident that the same are not visible from the top and consequently the cook is relieved from the flare of the flames. 95

The frame G supports a drip pan H a distance below the gas pipes A so that any drippings from the meat are directed downward over the sides of the hoods F into the drip pan H, which latter can be removed from time to time for emptying of the drippings. 105

By reference to Fig. 1 it will be noticed that the distributing pipe C is approximately 110

of inverted U-shape so as to provide an open space at the front of the stove for sliding the drip pan H into and out of position.

The front bar G' of the griddle frame G 5 is preferably provided with a handle G⁵ to permit the cook to conveniently slide the griddle frame in or out of position on the griddle side bars B² of the stove frame B.

When it is desired to use the broiler for 10 cooking purposes or for heating sad irons and the like a cover I Fig. 6 is used instead of the griddle frame G, the cover I being provided with depending sides I' provided with friction rollers I² slidably engaging 15 the bottoms of the grooves B' in the side bars B². It is understood that the cover I extends above the gas pipes A so that the cover is heated by the gas flames.

Having thus described my invention, I 20 claim as new and desire to secure by Letters Patent:

1. A gas broiler comprising a frame, a series of horizontal parallel gas pipes spaced apart and provided with perforations on 25 their upper sides, a griddle arranged above

the gas pipes and formed of a series of inverted V-shaped hoods, each arranged over and parallel to a gas pipe, the sides of the hoods extending below the perforated top of the pipes, as described. 30

2. A gas broiler comprising a main frame having grooved side bars, and a series of horizontal parallel gas pipes having perforations on their upper side, a griddle formed of a series of inverted V-shaped hoods each 35 arranged over and parallel to one of said gas pipes and extending down below the top of the perforated portion of the same, a frame in which the said hoods are rigidly secured, the sides thereof projecting downward and adapted to slide in the guideways 40 formed by the grooves of the main frame, as described.

In testimony whereof I have signed my name to this specification in the presence of 45 two subscribing witnesses.

GEORGE WESLEY MURRAY.
